COMBINED ICE MAKER AND ICE STORAGE CABINET

Raymond C. Young, Manitowoc, Wis., assignor to The Manitowoc Company, Inc., Manitowoc, Wis., a corporation of Wisconsin

Filed May 17, 1963, Ser. No. 74,925

Term of patent 14 years

(Cl. D67—3)

FIG. 1

The side not shown is substantially the same as the side shown, and the rear is substantially plain.

I claim:

The ornamental design for a combined ice maker and ice storage cabinet, substantially as shown and described.
